(57) **CLAIM**

The ornamental design for an injection device, as shown and described.

DESCRIPTION

FIG. 1 is a perspective view of an injection device, showing our new design;

FIG. 2 is a bottom-perspective view thereof;

FIG. 3 is a left-side view thereof;

FIG. 4 is a right-side view thereof;

FIG. 5 is a top view thereof;

FIG. 6 is a bottom view thereof;

FIG. 7 is a front view thereof; and,

FIG. 8 is a back view thereof.

The broken lines in the figures show portions of the injection device that form no part of the claimed design.
